UNITED STATES PATENT OFFICE.

JOHN H. BAUMAN, OF CONCORD, NEBRASKA.

HAY-STACKER.

No. 830,198.

Specification of Letters Patent.

Patented Sept. 4, 1906.

Application filed January 6, 1905. Serial No. 239,951.

To all whom it may concern:

Be it known that I, JOHN H. BAUMAN, a citizen of the United States, and a resident of Concord, in the county of Dixon and State 5 of Nebraska, have invented a certain new and useful Improvement in Hay-Stackers, as will be described more fully hereinafter and finally pointed out in the claim.

In the accompanying drawings I have 10 shown in Figure 1 an elevation of a hay-stacker embodying my invention with portions removed, while Fig. 2 shows an end view of my stacker.

In carrying out the aim of my invention I 15 use two runners A, of any suitable material, which are connected by means of the cross-sills to form a suitable portable base. The runners A at each end are provided with the links 19, so that suitable draft-animals may 20 be readily hitched to my hay-stacker.

Supported centrally upon the base d, secured to the cross-sills a, is a base-cone 3, suitably secured upon which rests the tubulous standard 1 of any suitable length and diameter and preferably of iron, which is provided below with the bearing 2, as shown in Fig. 1. Extending upward from the cross-sills a are the supporting-bars B, which above are secured to a collar C, suitably secured to these 25 standards, and extending through this collar 30 is the tubulous standard 1, as shown more clearly in Fig. 1. This tubulous standard is further provided with a bearing-shoulder 4, working upon the collar C, as shown. Above 35 this tubulous standard is slotted so that the crane b is suitably held within the slot of this standard, being secured by means of the pins 7, as shown in Fig. 1. The crane b is further secured by means of the supporting-bars 8

40 and 9, secured by the bolts 6', 7', and 8', as shown. Below this crane b the tubulous standard is perforated, so that the hoisting-cable c will readily pass through the standard, and in order to support this cable I provide 45 the sheave 5, secured to the pin 6, as shown in dotted outlines in Fig. 1. Near the forward end I provide the crane with the hook 11 and near the rear end with the hook 10. Secured to the hook 11 by means of the loop 50 13 is the block 15, over which the hoisting-cable passes, while secured to the hook 10 by means of the loop 12 is the second block

14, over which the hoisting-cable also extends. Secured to the central cross-sill a is a hook 17, as shown in Fig. 2, provided with 55 the block 18, through which the hoisting-cable also extends. At the forward end this hoisting-cable is provided with the ring 16, to which is secured an ordinary hay-fork E. Now by this arrangement the tubulous stand- 60 ard is revolvably supported, so that the same may be freely turned. Now in using this implement in making a stack the tubulous standard is so placed that the crane b will stand at right angles to a plane passing 65 through the sheave 18, and the axes of the tubulous standard, as is shown in Fig. 1, for instance. The fork E, having received its load, suitable draft-animal would be secured to the hoisting-cable c, and as these ad- 70 vance the freely-moving tubulous standard c would be swung around, so that the two sheaves 14 and 18 would come in alinement, resulting in the stack being made at a point 75 ninety degrees from the point where the load is received. Usually when the draft-animals are started they do two things, they raise the load as well as swing around the tubulous standard. It is of course understood that the load could be placed at a point at 80 any angle to the point where the load is received.

The device is neat and simple of construction and readily operated. When transported, the implement is carried upon the 85 runners A, while in being shipped the tubulous standard is removed from the collar C, the crane b being unshipped and the connecting-bars 8 and 9 removed. A simple truck can be readily placed below the runners A. 90

These stackers may be made of various sizes.

Having thus described my said invention, what I claim as new, and desire to secure by United States Letters Patent, is—

In a device of the character described, the combination with two runners, of cross-sills connecting said runners, a cone secured to one of said sills, supporting-bars extending upward from said sills, a collar, said supporting-bars at their upper ends being secured to said collar, a tubular standard extending through said collar and having its lower end resting upon said cone, a bearing-

shoulder secured to said standard, said shoulder resting upon said collar, the upper end of said standard being slotted, a crane held within said slot, supporting-bars extending 5 from said crane and being secured to said standard, said standard being perforated, pulleys secured to each end of said crane, and a hoisting-cable passing over said pulleys and

through said standard perforation, all arranged as set forth.

In testimony whereof I affix my signature in presence of two witnesses.

JOHN H. BAUMAN.
